UNITED STATES PATENT OFFICE

153,174

DESIGN FOR A PORTABLE POWER SANDER

Harry J. Riddle, Alameda, and Allan B. Walker,
Piedmont, Calif.

Application September 8, 1947, Serial No. 141,244

Term of patent 14 years

(Cl. D9—2)

To all whom it may concern:

Be it known that we, Harry J. Riddle and Allan B. Walker, have invented a new, original, and ornamental Design for a Portable Power Sander, of which the following is a specification, reference being had to the accompanying drawing, forming part thereof.

Figure 1 is a front elevation of a portable power sander, showing our new design.

Figure 2 is an end elevation thereof.

Figure 3 is a top plan view thereof.

We claim:

The ornamental design for a portable power sander, substantially as shown.

HARRY J. RIDDLE,
ALLAN B. WALKER.
